UNITED STATES PATENT OFFICE.

GIUSEPPE MUSSO, OF VADO, ITALY.

TRANSMISSION OF ELECTRICAL IMPULSES OVER CIRCUITS OF HIGH ELECTROSTATIC CAPACITY.

1,182,302.

Specification of Letters Patent.

Patented May 9, 1916.

Continuation of application Serial No. 626,851, filed May 12, 1911. Renewed January 12, 1914, Serial No. 811,732. This application filed August 13, 1914. Serial No. 856,579.

To all whom it may concern:

Be it known that I, GIUSEPPE MUSSO, a subject of the King of Italy, and resident of Vado, Province of Genoa, Italy, have invented certain new and useful Improvements in Transmission of Electrical Impulses Over Circuits of High Electrostatic Capacity, of which the following is a specification.

10 This invention relates to the transmission of electrical impulses over circuits of high electrostatic capacity, and, particularly, to a method of improving, both in quality and efficiency, the transmission of telephonic messages over long distance circuits, constituted of either cables or open wires.

This application is a continuation of my application filed May 12, 1911, Ser. No. 626,851.

20 In carrying out my invention, I impress upon the main line an impulse of predetermined characteristics, suitable to overcome the impedance of the line, this impulse being the result of the fluctuation or discharge 25 of the electromagnetic field produced by a suitably constructed solenoid inserted in a local circuit, such circuit containing a battery or other suitable source of electromotive force. By this arrangement, knowing 30 the characteristics of the main line, and, consequently, the retardation that an impulse would be subjected to, if sent directly from a battery, and the lag of the voltage behind the current, the self-inductance of 35 the local circuit can be adjusted so as to establish, in said circuit, conditions directly opposite to those existing in the main line, *i. e.* to cause the current to lag behind the voltage to an equal degree as the voltage 40 would otherwise lag or be retarded by the capacity of the main line. Thus, the impulse will start bearing the prevailing characteristics of the local circuit, but it will be gradually affected by the opposite characteristics of the main line circuit, until, upon 45 reaching the receiving end of the main line, the components of each impulse, *i. e.* the voltage and amperage will appear to be in phase, or nearly so, while no trace of the usual retardation in operating the line will 50 be experienced. By this process I do, virtually, reduce by neutralization the impedance of the line to its ohmic resistance only. This, however, is not the point that

marks the limit of my invention, in fact, 55 it is plain that in an ordinary circuit opposing a certain ohmic resistance, the volume of the impulses can be increased by increasing the current generating them. This, however, is not and cannot be a case of simple application to my invention, as the source of electromotive force (the battery, for instance), here is to be considered only as a primary means for generating electrical impulses. My working impulses are of an 60 electromagnetic nature, and are set up by the solenoid. This solenoid, forming part of an electromagnetic circuit, must be designed so as to possess a limit of saturation 65 suitable for the formation of impulses of the desired volume for a given ohmic resistance of the main circuit. Now, when the limit of saturation of a solenoid is reached, a larger supply of current would not be profitable and might be detrimental. 70

My invention, therefore, is not limited to the means of neutralizing the effect of electrostatic capacity in a given line, but includes also that of overcoming the ohmic resistance of said line by causing the same 80 solenoid to set up impulses of proper intensity in relation, specifically, to the ohmic resistance of that line.

In this application I have illustrated my invention as applied to a telephone circuit. 85

In the accompanying drawings, like parts in Figures 1 and 2 and in Figs. 3 and 4 have been given the same reference numerals.

Figs. 1 and 2 are diagrammatic views 90 showing one arrangement for telephonic circuits. Figs. 3 and 4 are diagrammatic views, illustrating an amplified form of my invention.

In the arrangement shown in Fig. 1 the 95 local circuit includes a battery 102, an adjustable inductance coil 103, adjustable condensers 112 and an adjustable non-inductive resistance —R— connected in parallel with the inductance coil 103, and a telephone transmitter 101. The main line is shown at 104 and a return line at 109, which may be used instead of the ground return through 108 and 107. A telephone receiver is shown at 110, which it is understood may 100 be located at a distant station.

The arrangement shown in Fig. 2 is similar to that shown in Fig. 1 but contains

in addition a second battery 111 which is connected in series with the transmitter 101. This battery is of greater potential than the battery 102. The batteries 102 and 111 are connected with the line 104—109 in opposite polarity so that normally the battery 111 will impress its polarity upon the line, but should the resistance of the transmitter circuit vary or the circuit open the weaker battery 102 will then impress its polarity upon the line.

Referring to Fig. 3 an adjustable battery is shown at 14, provided with a switch arm 15, pivoted at 16, by means of which the desired number of elements forming the battery 14 can be cut in. A solenoid or coil is shown at 12, whose inductance and output is adjustable by means of the sliding contact 11. A variable and adjustable condenser is shown at 17 and an adjustable non-inductive resistance at 18. 17^a is a block or plug provided for the purpose of cutting out the condenser 17 altogether when desired. A telephone transmitter is represented at 20, but this may represent any suitable transmitting device. 25 represents a telephone receiver. The main line from the transmitter to the receiver may be traced through 2, 3, 4, 23, and 28 and the return line through 29, 30, 5, 6, and 7.

The return line circuit may be by way of a ground circuit 21, 22 as shown in Fig. 4, which is similar to the diagram shown in Fig. 3, except in that the return line, 29, 30, 35 24, 5, 6 and 7 is eliminated and the line grounded at 21 and 22, and capacities or condensers 26, 27 inserted at the ends of the main line. Such condensers are intended, chiefly, to reduce, in its effect the electrostatic capacity of main circuits, such as lone aerial lines, underground or submarine cables. In all cases, where the electrostatic capacity of such main circuits is sufficiently large to cause undesirable effects, I have 45 found that the best results are obtained when said condensers are inserted in the main circuit some distance from the receiving device, as shown at 27 in Fig. 4.

The local circuit is outlined in Figs. 3 50 and 4 by the numerals 16, 1, 2, 7, 8, 9, 13.

The operation of the system will be understood from a description of that shown in Figs. 3 and 4, which is as follows: First, ascertaining the characteristics of the main line 23, I proceed to the adjustment of the inductance and output of the solenoid or coil 12, varying also, if necessary, the capacity 17, the resistance 18 and the battery 14, to produce conditions opposite to those existing in the main line and so proportioned as to balance or neutralize the electrostatic capacity of the main line, thereby establishing a condition or resonance in the two circuits. This leaves only the ohmic resistance of the main line to be overcome,

which I accomplish by increasing the output or intensity of the impulses from the inductance coil 12. This coil is constructed by using the least possible amount of iron in the core and the smallest number of turns of wire having the largest cross-section to give the impulses required. The low ohmic resistance of the coil and the small amount of iron in the core permits the rapid fluctuations of current in the coil and resultant rapid fluctuations in the intensity of the field, producing a discharge, or series of discharges, of maximum intensity sufficient to overcome the ohmic resistance of the line and to cause the impulses to reach the distant end of the main line having ample intensity or strength to operate the receiver. Having thus determined the desired characteristics and the intensity of the impulse to be used, I then operate the transmitting device 20, which, in this case, is a telephone transmitter. This, as it is well known, will determine variations in the resistance of the local circuit, 16—1—2—7—8—9—12, thereby causing corresponding fluctuations or variations in the magnetic field set up by the solenoid or coil 12. Such fluctuations or variations of the magnetic field of the solenoid 12 are reflected or impressed upon the line 23—24, and can be detected at the distant end by a receiver 25.

As many changes could be made in the above constructions and arrangements and many apparently widely different embodiments of my invention designed, without departing from the scope of the appended claims, I intend that all matter contained in the above description or shown in the accompanying drawings shall be interpreted as illustrative merely of operative embodiments of my invention and not in a limiting sense.

What I claim as my invention, and desire to secure by Letters Patent, is:

1. The herein described system for the transmission of electrical impulses, consisting of a local circuit containing a source of electromotive force, a telephone transmitter, a solenoid of predetermined self-inductance which is so proportioned as to balance or neutralize the electrostatic capacity of the main line and of predetermined output and intensity sufficient for overcoming the ohmic resistance of the main line upon which said impulses are impressed, and connections connecting said source of electromotive force and solenoid in series with the main line and said transmitter in shunt therewith.

2. Means for transmitting electrical impulses, over a main line, comprising a source of electromotive force and an adjustable inductance in series with said main line, an adjustable condenser in series with an adjustable non-inductive resistance connected in shunt with said inductance, and a tele-

phone transmitter connected in shunt with said source of electromotive force, inductance, condenser and resistance.

3. The herein described system for the transmission of electrical impulses over a main line, consisting of a local circuit containing a source of electromotive force an inductance of predetermined self-inductance so proportioned as to balance or neutralize the electro-static capacity of the main line, and a telephone transmitter for causing fluctuations or variations in the magnetic field of said inductance, and connections between said local circuit and main line connecting said source of electro-motive force and inductance in series with the main line and said transmitter in shunt therewith.

4. The herein described system for the transmission of electrical impulses, consisting of a local circuit containing a source of electromotive force, a telephone transmitter, and a solenoid of predetermined self-inductance which is so proportioned as to be adapted to establish impulses in said local circuit having characteristics which balance or neutralize the electrostatic capacity of the main line and of predetermined output and intensity sufficient for overcoming the ohmic resistance of the main line upon which said impulses are impressed, said main line being connected electrically with said local circuit between the transmitter and source of electromotive force on one side and solenoid and transmitter on the other.

5. The herein described system for the transmission of electrical impulses, consisting of a local circuit containing a source of electromotive force, a telephone transmitter, a solenoid of predetermined self-inductance which is so proportioned as to balance or neutralize the electrostatic capacity of the main line and of predetermined output and intensity sufficient for overcoming the ohmic resistance of the main line upon which said impulses are impressed, said main line being connected through condensers with said local circuit between the transmitter and source of electro-motive force on one side and the transmitter and solenoid on the other.

6. The herein described system for the transmission of electrical impulses of prede-

termined characteristics, adapted to overcome the impedance of a main line, said system consisting of the combination of a 55 variable source of electromotive force with an adjustable inductance coil connected in series therewith, said inductance coil being so proportioned as to balance or neutralize the capacity of the main line, and of a transmitting device in shunt therewith, these three elements being connected in a local circuit, from which said impulses are set upon the main line, said line being connected to said local circuit. 60 65

7. The herein described system for the transmission of electrical impulses of predetermined characteristics, adapted to overcome the impedance of a main line, said system consisting of the combination of a 70 variable source of electromotive force with an adjustable inductance coil, said inductance coil being so proportioned as to balance or neutralize the capacity of the main line, and of a transmitting device, 75 these three elements being connected in series in a local circuit, said transmitting device being connected in parallel with said source of electro-motive force and coil in respect to the line, from which said impulses 80 are set upon the main line, said line being connected to said local circuit.

8. The herein described system for the transmission of electrical impulses of predetermined characteristics over a main line, 85 consisting of the combination with said main line of a local circuit in which a variable source of electromotive force, a coil of adjustable inductance and output and a telephone transmitter are connected in series, 90 said telephone transmitter being connected in parallel with said source of electromotive force and coil in respect to the line, and a variable condenser connected in series with an adjustable non-inductive resistance connected in parallel with said inductance coil. 95

Signed at New York, N. Y. in the county and State of New York, this 11th day of August, 1914.
